To all whom it may concern:

Be it known that I, Melvin O. Hansen, a citizen of the United States and residing at Toledo, in the county of Lucas and State of Ohio, have invented a new, original, and ornamental Design for a Tumbler, of which the following is a specification, reference being had to the accompanying drawing, forming a part thereof.

In the drawing:

Fig. 1 is an elevational view of a tumbler showing my new design.

Fig. 2 is a top plan view thereof.

I claim:

The ornamental design for a tumbler, substantially as shown.

MELVIN O. HANSEN.
